(57) **CLAIM**

The ornamental design for the adjustable screen mount with tray, as shown and described.

DESCRIPTION

FIG. 1 is an elevated right front perspective view of the adjustable screen mount with tray;

FIG. 2 is an elevated rear left perspective view of the adjustable screen mount with tray;

FIG. 3 is a top plan view of the adjustable screen mount with tray;

FIG. 4 is a bottom plan view of the adjustable screen mount with tray;

FIG. 5 is a right side elevation view of the adjustable screen mount with tray, the left side elevation view being a mirror image thereof;

FIG. 6 is a rear elevation view of the adjustable screen mount with tray;

FIG. 7 is a front elevation view of the adjustable screen mount with tray;

FIG. 8 is an elevated right front perspective view of the adjustable screen mount with tray;

FIG. 9 is a bottom plan view of the adjustable screen mount with tray;

FIG. 10 is a top plan view of the adjustable screen mount with tray;

FIG. 11 is a right side elevation view of the adjustable screen mount with tray, the left side elevation view being a mirror image thereof;

FIG. 12 is a rear elevation view of the adjustable screen mount with tray; and,

FIG. 13 is a front elevation view of the adjustable screen mount with tray.

The adjustable screen mount with tray is shown without the tray in FIGS. 1-7 for clarity.
